MACHINE FOR REMOVING SNOW

Edwin B. Cadwell, Saugerties, N. Y.; Helen Cadwell executrix of said Edwin B. Cadwell, deceased

Application February 25, 1942, Serial No. 432,274

21 Claims.

(Cl. 37—43)

This invention relates to the art of removing material in situ and relates more particularly to the art of removing snow from city streets, highways and airports, on which it lies or is banked.

One of the principal objects of my invention is to provide a machine for removing material such as culm or snow lying in a bank, from the ground by slicing and gathering up directly from the mass a substantial portion of the same and delivering it to a place of deposit.

A further object of my invention is to provide a machine for progressively removing an upper portion of the mass of snow by slicing it and gathering it up and simultaneously scraping and lifting the lower remaining portion from its place, and delivering the combined product to a place of deposit.

A further object is to provide a machine for removing snow from the ground, having a projector, said projector being advanced directly into the snow-bank as it lies on the ground surface, for slicing and gathering up directly from the mass a substantial portion of the snow, instead of elevating it and forcing it through a funnel or by moving it with conveyors.

Another object is to provide a machine having a curved scraper blade placed close to the rear side of the projector for scraping a portion of the snow mass lying directly in contact with the road, and rolling it from the rear into a projector for delivery to a place of deposit.

Another object is to provide a machine that will work under the most unfavorable conditions of temperature and regardless of the density and hardness of the snow to be removed.

Another object is to provide a machine that will project the snow at a considerable distance from the place of removal by its own force.

Another object is to provide a machine having means to discharge the removed snow into a vehicle travelling alongside the carrier of said machine for transporting the material to a distant place of deposit.

Another object is to provide a machine that can be operated for a considerably smaller cost than the machines heretofore used for the same purpose.

Another object is to provide a machine that can be put on an existing truck or other vehicle projecting from and working at one side thereof.

Another object is to provide a self-propelled vehicle carrying a machine on its front or rear end or on the side thereof, for removing snow from the ground.

Another object is to provide a machine that

will work with great speed and efficiency due to its strong construction and powerful driving means.

Another object is to provide a machine having a projector and two curved scraper blades, one of which is placed close to the rear side of the projector for scraping a portion of the snow mass lying directly in contact with the road below the projector and rolling it from the rear into the projector; the other scraper blade is connected to one side of the first scraper blade and angularly adjustable thereto for scraping a snow mass lying directly in contact with the road at one side of the projector, and rolling it from the side into the projector.

Further objects and advantages of the invention will be in part set forth in the following specification and in part will be obvious thereto without being specifically pointed out, the same being realized and attained as pointed out in the claims hereof.

The most common method of removing snow is by means of displacement plows. Such means are successful in pushing or rolling any kind of snow from the road surface into windrows or banks along the roadside, except that which is very deep or very dense.

This method compacts the snow and under usual temperature changes, it soon becomes very dense, the lower strata becoming ice and the other surfaces very hard. These windrows frequently obstruct traffic and must be removed. Rotary, power driven removers are most efficient for this purpose.

Heretofore, rotary snow removers have been built on the principle of gathering and bringing the snow to the rotor-member which must be of relatively small diameter, and is usually shrouded in the small end of a forwardly projecting funnel shaped scoop, or by means of transversely operated screw type conveyors. These methods are successful when working in light, dry snow.

The old method of operation is to push the scoop or the screw conveyor into the snow, gathering all in its path and forcing same into the rotating member. If the snow is dry and light, much power is not required, but if the snow is dense and frozen, which is its usual condition, the operation entails the breaking up and tearing apart of a relatively solid mass and then recompacting it as it is forced into the rotor member. This requires great power and tractive effort.

These rotor members are most commonly constructed with flat surfaced blades mounted radi-

ally around a rotatable shaft all inclosed in a housing the front of which is open, also an opening in the periphery through which the snow is discharged.

Snow is of varying consistency, ranging from light and dry, weighing approximately 200 lbs. to the cubic yard, through varying conditions of dampness and density, to a weight approximately that of water, which is over 1,600 lbs. per cubic yard.

Light, dry snow can be crowded through a funnel shaped scoop and into a rotary remover member, but damp snow will compact and plug the passage, reducing efficiency even to the vanishing point, depending on the condition of this very unstable material.

These snow banks frequently become so dense and hard that even screw conveyors are ineffective, and it is necessary to break them up with power operated road grader blades and scarifiers, before the screw conveyors will perform their function.

My invention utilizes an improved method. I advance the rotor member into the snow as it lies on the road surface instead of elevating it and forcing it through a funnel or by moving it with conveyors. I thereby slice and gather up directly from the mass a substantial portion of the snow, with the expenditure of much less power and tractive effort and then scrape and roll the remaining snow into the path of the rotating member from the rear. I accomplish this by means of a curved scraper blade placed close to the rear face of the rotor member. The tractive effort required is thereby greatly reduced by reason of having first removed the upper strata of snow, and also because a curved blade is most efficient in moving material.

Loading the rotor member from both front and rear permits the full loading of same; also better compacting of the snow thereby further increasing efficiency.

To implement this method, I have provided an apparatus which will compact and throw the snow to either side to a considerable distance, or into a windrow adjacent, or into a truck for remote disposal, only requiring the power furnished by any one of several makes of light truck engines.

The rotor member comprises a plurality of scoop shaped shovels with sharp cutting edges, mounted radially on a rotatable shaft so tied together and reinforced that it will cut and gather any form of snow or ice to be encountered in snow banks.

It is not shrouded, and when projected into the snow, operates like a boring mill cutter, except that it both cuts and gathers its chips with its front, rear and peripheral faces.

The more densely the snow can be packed into the rotor member, the less power is required to throw same a given distance; hence, I build these shovels in the form of deep scoops which facilitates compression.

When discharging snow into a truck body, care must be taken, otherwise it may be packed so hard it can't be dumped. Therefore, I provide means for changing the speed of the rotor member enabling control of velocity of the snow stream.

My apparatus can be carried on the front of a standard truck in manner similar to a displacement plow or on a special chassis to be drawn or pushed by truck or tractor.

With the above and other objects of the in-

vention in view, the invention consists in the novel construction, arrangement and combination of various devices, elements and parts, as set forth in the claims hereof, certain embodiments of the same being illustrated in the accompanying drawings and described in the specification.

In the accompanying drawings which form part of my specification:

10 Fig. 1 is an elevational view of the front of the machine mounted on a vehicle;

Fig. 2 is a side elevation of the same and showing the vehicle only in part, without showing a chute;

15 Fig. 3 is a top view of the same;

Fig. 4 is a rear view of the same, in elevation;

Fig. 5 is a side elevation of a modification in which the driving motor for the projector is mounted near, and adjustable in vertical position together with, the same;

20 Fig. 6 is a peripherical section through the buckets two of them being illustrated;

Fig. 7 is a cross section through a bucket taken along the line 7—7 of Fig. 6;

25 Fig. 8 is a top view of a truck of usual construction carrying a projector and motor, the projector being located at one side thereof, the chute being not shown;

30 Fig. 9 is a side view of a modified embodiment of a chute;

Fig. 10 is a cross section of the connecting pieces taken along line 10—10 of Fig. 9;

Fig. 11 is a side view similar to Fig. 9 showing a portion of the chute in another position; and

35 Fig. 12 is a side view of the chute, a portion of which is shown in a position different from the previous positions.

In the description of the drawings in which similar numerals designate similar parts throughout, a machine-frame 19 is connected to a frame 10 of a vehicle, and is vertically adjustable with relation thereto.

The connection between the vehicle-frame 10 and the machine-frame 19 is provided by substantially parallel levers 43 and 38 respectively, each lever being pivoted with one end to the frame 10 and with the other end to the frame 19 or to an element in turn rigidly secured to said frame 19. The upper lever 43 is pivotally mounted to the lower end of a lever 44 slotted at 44', the upper end of which is connected to a manually operable hoist 45, said lever 44 being surrounded by a spring 49, the lower end of which bears against the lever 43 and the upper end of which is secured to said lever 44, for providing a resilient connection between the lever 43 and the hoist 45, said hoist being secured to said vehicle-frame 10. A resilient and adjustable connection between the vehicle-frame 10 and the machine-frame 19 is thus provided, for resiliently holding the elements carried by said machine-frame 19 in a predetermined and adjustable vertical position with relation to the ground on which the vehicle travels.

65 In the modification shown in Fig. 5, the upper lever 43 and therewith the frame 19 and the elements secured thereto comprising the motor 24, are held in resilient and adjustable position by means of a combination comprising an air cylinder 55 and a piston coactive therewith, the vertical position of said frame 19 being determined by the relative position of the piston in said air cylinder 55 which is controlled by the amount of air therein.

70 The frame 10 carries axles 11 which in turn

carry running wheels 12. A revolvable projector or rotor 13 is secured to the machine-frame 19 and consists of a rotatable shaft 14, the axis of which is parallel to the longitudinal axis of the vehicle, and a plurality of scoop-shaped shovels or buckets 15 radially mounted on said shaft 14 and tied together by links 16 near the outer periphery 17 formed by said buckets 15. These buckets are of U-shaped cross-section and are open on the top of the outer peripherical circle 17, and are flaring outwardly near the forward edges 18, being reinforced there by reinforcing bars 20 having cutting edges, said edges projecting sidewise, sufficiently to form the outermost projections of the rotor 13. Each link 16 ties together two of the buckets 15.

The forward end of each link 16 is threaded and protrudes into a pocket 21 through a hole provided therein at the rear of each bucket 15 and is held in said pocket 21 by a nut 29; on its rear end the link 16 is provided with a loop 22, said loop embracing a transversal cutting member 23 of said reinforcing bars 20, the edges of which form the outermost cylindrical periphery of said rotor 13 (see Figs. 6 and 7).

Together with said projector 13, blades 41 and 52, shoes 46, chutes 26 and 34, a plow member 39, and a wall plate 36 are mounted on said machine-frame 19 and are vertically adjustable therewith relative to the vehicle-frame 10 and, therefore, to the vehicle itself.

A motor 24 is carried by the vehicle-frame 10 and drives the shaft 14 of said rotor 13 by means of a chain 25 or other suitable driving means.

In the modification shown in Fig. 5, the motor 24 is carried by the machine-frame 19 together with the other elements as listed above and is vertically adjustable together therewith.

Continuing the description of the embodiment shown in Figures 1 to 4, the chute 26, mounted on the machine-frame 19, is of U-shaped cross-section throughout its length, the lowest portion of said chute being located adjacent the periphery 17 of said projector 13 and substantially on the level of the horizontal shaft 14 thereof; the chute 26 is open toward the projector 13 and with its lower portion surrounding the same in part. The chute is composed of a fixed portion and a plurality of articulated sections, said fixed portion being secured to the frame 19; the position of said articulated sections can be selectively adjusted by the operator of the machine, the adjustment being attained by a manually operable worm gear and a worm, 21, mounted on the fixed portion of said chute, the axis of rotation of said worm gear coinciding with the axis of pivot between said fixed section and an articulated section 28. A shaft 29 and two universal joints 30 at both ends thereof connect said worm with a handwheel placed at a distance from said worm gear on the frame 19. Thereby the section 28 and with it a section 30 which is adjustably hinged thereto may be thrown into the position shown in broken lines in Fig. 4, or into any position therein between. The section 30 can be adjusted in its position relative to the section 28 by means of a handwheel 32 secured to the hinge connecting the two sections. The lowest section 33 embracing in part the projector as pointed out and as indicated in Fig. 1, is hinged to the section fixed to the machine-frame 19 and may be swung upward into a vertical position shown in broken lines and adjusted in that position similar to the adjustment between the sections 28 and 30, thereby forming a connection to a second chute

34. Said chute 34 is also of U-shaped cross-section, the open side of which, however, is opposite the side on which the projector 13 is located.

Said chute 34 is pivotally connected to the machine-frame 19 at 35 and the angular position thereof relative thereto is adjustable by means similar to the means employed in adjusting the sections 28 and 30 of the chute 26 relative to each other, or by other suitable means.

A curved scraper blade 41 or mould board is rigidly connected to the machine-frame 19 and placed adjacent the rear side of the projector 13 and facing it with its concave side, and provided near its lower end with a pivot 37 for connection to the lower lever 38.

A curved gathering blade 52 (Fig. 3), hinged at 53 to one side of the blade 41, and connected to the frame 19 by a link 54 is provided to gather snow that may be in its path and roll the same near and into the cylindrical periphery of the projector 13 from the side.

A plurality of shoes 46 are sliding on the ground and are hinged to the scraper blade 41 near the lower edge thereof, and are also hinged to a threaded rod 47 reaching into and adjustably held by a receiving member 48 which member is rigidly secured to the blade 41. The adjustment between the receiver 48 and the rod 47 is attained by means of two threaded nuts 50. This mechanism comprising the shoes 46 is provided for the support of the blade 41 and thereby also of the machine-frame 19.

A wall 36 is secured to the machine-frame 19 and extends downward to the bottom of the blade 41.

The plow member 39 is mounted on the machine-frame 19, adjacent the outside of said projector 13 and projecting forward therefrom, extending downward to the level of the shaft 14 and upward therefrom beyond the highest point of said machine-frame 19, for slicing and rolling the part of the snow bank above the axis of the rotor into the path thereof, as the vehicle travels forward.

The operation of my invention has in part been set forth in the preceding description and may be readily understood by those skilled in the art without describing it in further detail, and only a few additional explanations in the following are deemed necessary to complete the information on the subject of operation:

The two chutes 26 and 34 respectively, are adapted to receive the snow masses gathered by the rotor and to deposit said masses at a selected place. The snow is sliced from the mass lying on the ground by the cutting edges of the bars 20, and by the transversal cutting members 23 of the rotor 13; the product thereafter is collected by the buckets 15, and by centrifugal power is forced out of the buckets and into the chute 26 with such a speed that it will move rapidly through that chute and leave the same in a direction determined by the position of the last section thereof.

While the snow is sliced from the mass, the curved scraper blade 41 scrapes and rolls the snow remaining on the ground below the projector 13 into the path of the same from the rear; this scraping takes place along a line at a distance behind the slicing, substantially equaling the depth of the rotor, with relation to the travelling movement of the vehicle.

Simultaneously, the gathering blade 52 gathers any snow that may be in its path and rolls the same into the projector 13 from the side, so that

the projector will receive the snow radially and slice it with the transversal cutting members 23.

The section 28 of said chute 26, may be moved into the position shown in Fig. 4 in broken lines, thereby permitting the snow to continue to fly in the direction of the fixed section after leaving the same. By this arrangement the product may be thrown into the open air. In the usual position of the sections of the chute 26, as shown in Fig. 1, the snow may be deposited in a truck or railroad car moving alongside the vehicle comprising the machine.

When the lower section 33 of the chute 26 is swung and held upward by means hereinabove described, the product will travel straight upward along the wall 36 instead of moving up the chute 26, and will follow the channel of the chute 34 and will be directed to the opposite side of the vehicle than by using the chute 26. Following the adjustment of the position of the chute 34 the snow may be thrown into an open space or into a truck travelling alongside the vehicle comprising the machine.

The hoist 45 and the air cylinder 55 respectively, serve to adjust and hold resiliently the position of the rotor 13 and the curved blades 41 and 52 in relation to the ground, and the adjustment may be made by the operator in accordance with the conditions of density of snow or of hardness of the road.

The shoes 46 supporting the curved blade 41 aid to serve the purpose to prevent the scraper blade from cutting into the ground itself by lifting and lowering it according to the unevenness of the ground surface while sliding thereon.

In the embodiment shown in Figs. 9-12 inclusive, the chute 26 comprises a fixed section and two articulated sections 28 and 30, and the position of said articulated sections may be changed with relation to the fixed portion of the chute by means of a worm and worm gear, 27, as heretofore described, or by any other suitable means controlled by the operator of the machine.

It is desirable to determine with a single control means the direction of ejection of the snow masses from the chute to enable the operator to control the distance and direction in which the snow masses shall be deposited, by turning a single wheel only.

In this modification simple means are employed to attain this desired end; by raising the articulated section adjacent the fixed portion of the chute the other articulated section, which constitutes also the termination of the whole chute, is turned downward, and vice versa.

In carrying this modification into effect I provide two tubes 61 and 62, respectively, which telescope into each other, each of said tubes being pivoted at its end to a different section of the chute; the tube 61 has a greater diameter than the tube 62, and is pivoted to the outside of the articulated section 30 at the pivot point 60. The tube 62 is pivoted at the pivot point 65 to the outside of the fixed portion of the chute. The open end of the tube 62 telescopes into the open end of the tube 61 and may be secured in this position by means of a threaded bolt 63, carrying a threaded nut 64 thereon (see Fig. 10). The outside diameter of the smaller tube 62 is only slightly smaller than the inside diameter of the larger tube 61; the two tubes, when telescoped into each other and secured in this position by means of the bolt 63, provide a stiff and pivotal connection between the outermost articulated section 30 and the fixed portion of the chute 26.

In the position of the chute shown in Fig. 9 the snow mass will leave the chute in a direction under a sharp angle with relation to the ground and may travel a fairly great distance to the place of deposit.

When the section 28 is raised into the position shown in Fig. 11 or into a still higher position, the rigid connection between the section 30 and the fixed portion of the chute will turn the section 30 downward into a position directing the snow under a greater angle with relation to the ground, for depositing it in a place near the machine and allowing the snow to travel only a short distance from the machine. This position of the chute will be used for depositing the snow into the body of a truck travelling alongside the vehicle carrying the machine.

It is often desired to deposit the snow at a great distance from the machine, for instance, when the snow is thrown into the open space alongside a highway in the countryside; this end may be attained by moving the articulated sections into the position shown in dotted lines in Fig. 4, and, furthermore, shown in Fig. 11:

After detaching the bolt 63 from the two telescoping tubes 61 and 62, respectively, the operator will swing the sections 28 and 30 into the position shown in Fig. 11. The two tubes will still telescope in this position. The snow to be discharged will leave the chute in the direction of the fixed portion thereof and, owing to the great discharge-speed, will travel a considerable distance from the machine.

I do not limit myself to the particular details of construction set forth in the foregoing specification and illustrated in the accompanying drawings, as the same refer to and set forth only certain embodiments of the invention and it is obvious that the same may be modified, within the scope of the appended claims, without departing from the spirit and scope of the invention.

Having thus described the invention, what I claim as new and desire to be secured by Letters Patent, is as follows:

1. A machine for removing material such as snow lying in a bank on the ground, said machine, being mounted on a vehicle, comprising, in combination, a frame, a motor carried thereby, a machine-frame supported with relation to said frame, a revolving projector driven by said motor and mounted on said machine-frame in position to be moved axially into said material by forward motion of the vehicle, said projector being adapted to slice the material from said bank, and a blade connected with relation to said machine-frame located near the rear of said projector, adapted to lift and to convey material from the ground from the rear into the projector as the vehicle travels forward.

2. A machine for removing material in situ such as snow lying in a bank on the ground, said machine, being mounted on a vehicle, comprising, in combination, a frame, a motor carried thereby, a machine-frame supported with relation to said frame, a revolving projector mounted on said machine-frame and driven by said motor, said projector being adapted to slice the material from said bank, the axis of rotation of said projector being parallel to the longitudinal axis of said vehicle, and a blade connected with relation to said machine-frame located near the rear of said projector adapted to lift and to convey material from the ground from behind into the projector as the vehicle travels forward.

3. A machine for removing material in situ

such as snow lying in a bank on the ground, said machine, being mounted on a vehicle, comprising, in combination, a frame, a motor carried thereby, a machine-frame supported with relation to said frame, a revolving projector mounted on said machine-frame and driven by said motor, said projector being adapted to slice the material from said bank, and a blade connected with relation to said machine-frame located near the rear of said projector, adapted to lift and to convey material from the ground from behind into the projector as the vehicle travels forward.

4. A machine for removing material in situ such as snow lying in a bank on the ground, said machine, being mounted on a vehicle, comprising, in combination, a frame, a motor carried thereby, a machine-frame supported with relation to said frame, a revolving projector mounted on said machine-frame and driven by said motor, said projector comprising a rotatable shaft and a bucket carried thereby, the outer periphery of rotation of said bucket being located near the surface of the ground on which the vehicle travels, said bucket comprising means adapted to slice the material to be removed, and a blade connected with relation to said machine-frame located near the rear of said projector, adapted to lift and to convey material from the ground from behind into the projector as the vehicle travels forward.

5. A machine for removing material in situ such as snow lying in a bank on the ground, said machine, being mounted on a vehicle, comprising, in combination, a frame, a motor carried thereby, a machine-frame supported with relation to said frame, a revolving projector mounted on said machine-frame and driven by said motor, said projector comprising a shaft and a plurality of buckets carried by said shaft and arranged in a circle and linked to each other near the outer periphery of said circle, said periphery being located near the surface of the ground on which the vehicle travels, said buckets comprising means formed to slice the material to be removed, and a blade connected with relation to said machine-frame located near the rear of said projector, adapted to lift and to convey material from the ground from behind into the projector as the vehicle travels forward.

6. The combination with a vehicle, of a machine for removing material in situ such as snow which is banked on the ground, comprising, in combination, a power driven revolving projector adapted to slice and collect the material to be removed, and a blade located near the rear of said projector adapted to lift and to convey material from the ground from behind into the rear of the projector as the vehicle travels forward.

7. A machine for removing snow comprising a vehicular support, a frame mounted on the forward end of the support, means for adjusting the frame vertically with respect to the support, said frame carrying a rotor adapted to be propelled in direct engagement with snow for removal, the rotor having its axis of rotation in fixed relation to the frame and parallel to the direction of movement of the machine, motor means for driving the rotor, and a curved blade extending transversely of the machine rearwardly of and below the rotor, whereby snow lying on and adjacent the ground is delivered into the rear of the rotor.

8. A machine for removing snow comprising a vehicular support, a frame mounted on the forward end of the support, means for adjusting

the frame vertically with respect to the support, a blade extending heightwise of the frame and having its cutting edge forwardly disposed, said frame carrying a rotor adapted to be propelled in direct engagement with snow for removal, the rotor having its axis of rotation in fixed relation to the frame parallel to the direction of movement of the machine, a point on the periphery of the rotor being in close adjacency to said blade, motor means for driving the rotor, and a curved blade extending transversely of the machine rearwardly of and below the rotor, whereby snow lying on and adjacent the ground is delivered into the rear of the rotor.

15 9. In a snow removing machine, the combination of a rotary projector, means for moving said projector axially into a snow mass, means for rotating said projector as it is moved axially forward to slice snow from an upper portion of the mass and project it toward a place of deposit, and a curved blade positioned adjacent the rear side of the projector and extending transversely of the axis thereof to remove snow lying on and adjacent the ground and deliver it into the projector from the rear.

20 10. In a snow removing machine, the combination with a vehicle, of a supporting frame, a rotary projector carried by said frame and positioned for axial movement into the snow mass by forward motion of the vehicle, means for rotating said projector, a curved blade extending transversely of the axis of the projector and positioned rearwardly of and closely adjacent the projector, to remove snow lying on and adjacent the ground and deliver it into the projector from the rear, and a second blade extending forwardly and laterally of said first blade to deliver snow laterally to the projector.

25 11. A machine for removing snow, comprising a vehicular support, a frame mounted on said support, means for adjusting the frame vertically with respect to the support, a rotor carried by said frame in position to be propelled axially into direct engagement with snow to be removed, said rotor having its axis of rotation in fixed relation to said frame, motor means for driving the rotor and a curved blade extending transversely of the axis of the rotor and positioned rearwardly of and lower than the rotor to remove snow lying on and adjacent the ground and deliver it into the rotor from the rear.

30 12. In a machine for removing material in situ, such as snow lying in a bank on the ground, the combination with a vehicle, of a revolving projector carried thereby and adapted to slice the material from a bank, means to revolve the projector, and a blade carried by the vehicle and disposed proximate the rear of the projector and shaped to lift and convey material from the ground forwardly into the rear of the revolving projector.

35 13. In a machine for removing material in situ, such as snow lying in a bank on the ground, the combination with a vehicle, of a revolving projector carried thereby and adapted to slice the material from a bank, means to revolve the projector, a blade disposed proximate the rear of the projector and adapted to lift and convey material from the ground forwardly into the rear of the revolving projector, a shoe and means to support the blade from the shoe at a predetermined elevation above the ground.

40 14. In a machine for removing material in situ, such as snow lying in a bank on the ground, the combination with a vehicle, of a revolving

projector carried by the vehicle and adapted to slice the material from a bank, means to revolve the projector, a blade disposed proximate the rear of the projector and adapted to lift and convey material from the ground into the rear of the revolving projector, a shoe and means to adjustably support the blade from the shoe at a predetermined elevation above the ground.

15. In a machine for removing material in situ, such as snow lying in a bank on the ground, the combination with a vehicle, of a revolving projector carried by the vehicle and adapted to slice the material from a bank, means to revolve the projector, a blade disposed proximate the rear of the projector and adapted to lift and convey material from the ground into the rear of the revolving projector and a blade carried by the vehicle and adapted to gather snow and direct the same proximate and into the periphery of the projector.

16. In a machine for removing material in situ, such as snow lying in a bank on the ground, the combination with a vehicle, of a revolving projector carried by the vehicle and adapted to slice the material from a bank, means to revolve the projector, a curved blade disposed proximate the rear of the projector and adapted to lift and convey material from the ground into the rear of the revolving projector and a curved blade carried by the vehicle proximate the periphery of the projector and adapted to gather snow and direct the same proximate and into the periphery of the projector.

17. In a machine for removing material in situ, such as snow lying in a bank on the ground, the combination with a vehicle, of a revolving projector carried by the vehicle and adapted to slice the material from a bank and a curved blade carried by the vehicle and disposed proximate the rear of the projector and adapted to lift and convey material from the ground into the rear of the revolving projector.

18. In a machine for removing material in situ, such as snow lying in a bank on the ground, the combination with a vehicle, of a revolving projector carried by the vehicle and adapted to slice the material from a bank and a blade car-

ried by the vehicle and disposed proximate the rear of the projector and whereof the bottom edge is disposed forwardly of the rear marginal plane of the projector, said blade being adapted to lift and convey material from the ground into the rear of the revolving projector.

19. In a machine for removing material in situ, such as snow lying in a bank on the ground, the combination with a vehicle, of a revolving projector carried by the vehicle and adapted to slice the material from a bank and a downwardly and forwardly curved blade carried by the vehicle and disposed proximate the rear of the projector and adapted to lift and convey material from the ground into the rear of the revolving projector.

20. In a machine for removing material in situ, such as snow lying in a bank on the ground, the combination with a vehicle, of a revolving projector carried by the vehicle and adapted to slice the material from a bank and a blade operatively connected with the vehicle and disposed proximate the rear of the projector and whereof the bottom edge is downwardly and forwardly curved and is disposed forwardly of the rear marginal plane of the projector, said blade being adapted to lift and convey material from the ground into the rear of the revolving projector.

21. A machine for removing snow comprising a vehicular support, a frame mounted on the forward end of the support, means for adjusting the frame vertically with respect to the support, said frame carrying a rotor adapted to be propelled in direct engagement with snow for removal, a generally upwardly extending blade having its cutting edge laterally of and forwardly of the rotor and thereabove, the rotor having its axis of rotation in fixed relation to the frame and parallel to the direction of movement of the machine, motor means for driving the rotor, and a curved blade extending transversely of the machine rearwardly of and below the rotor, whereby snow lying on and adjacent the ground is delivered into the rear of the rotor.

EDWIN B. CADWELL.
